UNITED STATES PATENT OFFICE.

HARMON WATSON, OF CULLMAN, ALABAMA.

RAILWAY-TIE AND FASTENER.

1,090,258.

Specification of Letters Patent. Patented Mar. 17, 1914.

Application filed October 11, 1913. Serial No. 794,696.

To all whom it may concern:

Be it known that I, HARMON WATSON, a citizen of the United States, residing at Cullman, in the county of Cullman and State 5 of Alabama, have invented certain new and useful Improvements in Railway-Ties and Fasteners, of which the following is a specification, reference being had to the accompanying drawings.

10 This invention relates to new and useful improvements in railway ties and fasteners and more particularly to a metallic railway tie provided with new and improved rail fastening means, the object of the invention 15 being to provide a metallic railway tie which is adapted to replace the wooden tie in use at the present time and which at the same time is provided with novel fastening means whereby the rails of the track may be securely held in position, upon the ties.

A further object of the invention is the provision of a metal tie having longitudinal slots formed in each end thereof and further provided with transverse recesses to receive the rails. Fastening members are 25 mounted for pivotal movement within said slots and are adapted to normally engage the inner base flanges of the rails to securely retain the rails within the transverse recesses 30 of the tie.

A further object of the invention is the provision of a metallic railway tie and fastener of the above type which will possess advantages in points of efficiency and durability, is inexpensive of manufacture and at the same time is simple in construction and operation.

With the above and other objects in view, the invention consists in the novel features 40 of construction and the combination and arrangement of parts to be hereinafter more fully described, pointed out in the claims and shown in the accompanying drawings, in which—

45 Figure 1 is a top plan view parts being broken away and in section; Fig. 2 is a side elevation, parts being broken away and in section; Fig. 3 is a longitudinal sectional view illustrating the rail in position; and 50 Fig. 4 is a similar view illustrating the rail about to be placed in position.

Referring more particularly to the drawings, 1 indicates the elongated body of the tie which is provided adjacent each end with the longitudinal slots 2 and is further provided at the outer ends of the slots with the

transverse recesses 3 which are formed in the top of the tie and are adapted to receive the base flanges of the rails. The recesses 3 are provided upon the outer sides thereof with the undercut side walls 4 beneath which the outer base flanges of each of the rails are arranged, the opposite side wall of the recess being perpendicular, as illustrated at 5.

Arranged between the side walls of the slots 2 are my improved fastening members, each of which comprise an elongated body portion 6 which is pivotally mounted upon the transverse pin 7 which extends through the entire width of the body. Formed at one end of the body 6 is an outwardly projecting lug 8, the outer face of which is curved, as shown at 9, while the under face thereof is inclined rearwardly toward the body, as shown at 10, and is formed coincident with the inclination of the base portion of the rails and adapted to engage thereover when the rails are arranged within the recesses 3. It will be noted that the lugs 8 upon each of the body portions are spaced from the body so that the base flanges of the rails will be tightly arranged between the body and the lugs when the body portion is in its operative position.

From the accompanying drawings, it will be readily apparent that when the lug 8 is in its operative position, the inclined inner wall 10 thereof will be arranged in opposed relation with the inclined wall 4 and will engage the base flange of the rail so as to securely hold the same in position. When a fastening member is arranged in its operative position, the elongated body 6 is disposed in a plane parallel with the body 1, as illustrated in Fig. 3, and is securely held against pivotal movement so that the inclined wall 10 engages with the base flange of the rail so as to securely retain the tie in position. In order to provide suitable means for retaining the fastening members in their operative position, the lower side of the body member 6 is provided at one end with a tapering notch 11, in which is adapted to be disposed the removable pin 12 which is inserted within the opening 13 in the body 105 of the tie and extends across the slots 2.

The retaining pins 12 are preferably wedge shaped in form and are provided at one end with screw threads whereby a retaining nut 14 may be removably engaged therewith to securely hold the pins in position.

It will be readily apparent that in placing a rail in position, the same is tilted so that one edge thereof will readily engage beneath the inclined wall 4, the rail will then 5 be dropped into the recess 3, and the lug 8 engaged over the opposite base flange of the rail, said lug being retained in its operative position by means of the transverse pins 12.

From the above it will be apparent that 10 after the rails have been placed in position and the lugs 8 engaged with the base flanges thereof, there will be little or no movement on the part of the rails as they are not only arranged within the recesses 3 but are securely held in position by the lugs.

It will be apparent that the device in 20 itself is extremely simple in construction, it being understood that the tie, while preferably formed of metal may be constructed of plastic material such as reinforced cement or any other suitable material desired.

It will be apparent that the formation of 25 the ties at switch points may be alternated so as to adapt the same to the sliding of the switch rails in opening and closing the switches.

While I have shown and described the preferred form of my invention, it will be obvious that various changes in the details 30 of construction and in the proportions may be resorted to for successfully carrying my invention into practice without sacrificing any of the novel features of construction or departing from the scope of the appended 35 claims.

It will be readily apparent from the construction of my invention that the same may be used at the meeting ends of the rails to securely hold the same against lateral movement and also to be substituted for the usual 40 fastening means now in use. It will be apparent that where my invention is used at the meeting ends of two rails, the tie must be somewhat wider than the usual tie and

the fastening member is to be of sufficient 45 width so that it will engage both ends of the tie sufficiently to hold the same against lateral or other movement. It will also be apparent that the device may be used at switch points or at any other place where the same 50 may be used with success.

What I claim is:-

1. A device of the class described including clamping members, outwardly projecting lugs formed at one end of each of said 55 clamping members and spaced from the body portions thereof, said clamping members being provided at their opposite ends and upon their opposite longitudinal edges with tapering notches as and for the purpose set 60 forth.

2. The combination with a tie having longitudinal slots formed therein adjacent each end and further provided with transverse recesses communicating with the slots at one 65 end thereof and adapted to receive the base flanges of the rails, of clamping members pivotally mounted within said slots, outwardly projecting lugs formed on one end of each of the clamping members and adapted 70 to engage over the base flanges of the rails, said lugs being spaced from the body portions of the clamping members to provide recesses for the reception of the base flanges of the rails and said clamping members being provided at their other ends and upon their opposite longitudinal edges with tapering notches, and means carried by the tie 75 and engaged within said notches to retain the clamping members in their operative position.

In testimony whereof I hereunto affix my signature in the presence of two witnesses.

HARMON WATSON.

Witnesses:

GEORGE H. REID,
JAMES L. WATSON.
